UNITED STATES PATENT OFFICE

CHESTER A. GRAINGER, OF CYNWYD, PENNSYLVANIA, ASSIGNOR TO ALBESTOS CORPORATION, OF PHILADELPHIA, PENNSYLVANIA, A CORPORATION OF PENNSYLVANIA

DESIGN FOR A DISPLAY CABINET

Application filed March 19, 1931. Serial No. 39,141. Term of patent 7 years.

To all whom it may concern:

Be it known that I, CHESTER A. GRAINGER, a citizen of the United States, and a resident of Cynwyd, county of Montgomery, State of Pennsylvania, have invented a new, original, and ornamental Design for a Display Cabinet, of which the following is a specification, reference being had to the accompanying drawings, forming part thereof, in which:—

Fig. 2 is a rear view.

I claim:—

The ornamental design for a display cabinet, substantially as shown.

CHESTER A. GRAINGER.
